UNITED STATES PATENT OFFICE.

EWART G. SINCLAIR, OF CASPER, WYOMING, ASSIGNOR TO THE MIDWEST REFINING COMPANY, OF DENVER, COLORADO, A CORPORATION OF MAINE.

METHOD OF MINING OIL AND THE LIKE.

Application filed August 10, 1925. Serial No. 49,254.

The invention relates to a novel method of mining deposits which produce or are associated with lethal or combustible gases, such, for example, as oil bearing sands, shale and the like, and has for its object not only to extract or recover the valuable mineral elements from the deposits, such as oil, but also to recover the gas produced by or associated therewith and utilize the recovered gas to the best advantage. To these ends, the invention comprises conducting the mining operations, in those portions of the workings in which the gas is present, in an atmosphere of such gas and with a practical exclusion of air from the workings, the operations being carried out by operators equipped with respiratory apparatus, of well-known types, which supplies the operators with the necessary complement of air or oxygen gas without permitting the escape of any of the latter.

An application of the invention, involving a typical installation of means for carrying out the method in the recovery of oil from a subterranean stratum is illustrated in the accompanying drawing, but it is to be understood that the illustration is merely exemplary and, in no sense, limiting.

Various methods of mining oil or other gas producing deposits have been suggested heretofore and some of these methods have been practically applied, but, in each instance, during the mining operations, in so far as the same have been conducted by man power, it has been regarded as absolutely necessary to free the workings in which the men operate of the combustible or lethal gases, because of the danger of violent explosions of the combustible gases when mixed with air, on the one hand, and of the effect of the poisonous or suffocating gases on the miners, on the other. According to the usual practice, the dangerous gases are excluded from the workings either by forcing said gases out of the workings by heavy drafts of air or by preventing the gas from entering the drifts or workings where the men are engaged by forcing air, under heavy pressure, into the face of the working, the object of these alternative operations being to prevent sufficient gas entering the working at any time to form with the air an explosive mixture. Successful operations of this kind, however, have been found practically impossible of accomplishment on a commercial scale, as in all oil or gas horizons there are areas of high

pressure as well as low pressure gas, so that it is next to impossible to maintain the air pressure against the working face at exactly the right pressure to prevent the escape of gas, and it is also difficult and expensive to regulate the air currents to sweep out the dangerous gases, when the alternative method is practiced. These methods, involving the employment of air either to sweep out dangerous gas or to confine the same within the face of the working, have proven to be not only highly expensive, but have resulted, in many instances, in heavy loss of life due to explosions, as the least spark will ignite a mixture of air and combustible gas, when the proportions of air and gas are right.

According to the present invention, it is proposed to carry out the mining operations in the workings under a substantially total exclusion of air and in an atmosphere of the gases produced in the mine, or of similar gases supplied to the workings, thereby eliminating the possibility of explosions as the gases are not combustible per se, the miners operating in said gaseous atmosphere being equipped with suitable kits of respiratory apparatus, such, for example, as those employed in mine rescue work.

Referring to the accompanying drawing, which illustrates the invention as applied to mining an oil bearing stratum, 1 indicates the mine shaft, which may be sunk to penetrate any or all of the strata encountered, which latter may be in the form of oil bearing sands, shale beds or other oil bearing formations, which shaft is equipped with the usual derrick 2 at the top thereof from which the elevator or hoist 3 is operated in the shaft by cables 4, all of which is common mining practice generally. Where the shaft 1 is intersected by the drift 5, which leads to the working represented by the breast 6 of the oil bearing stratum, the drift is provided with an air-lock comprising spaced partitions 10, 10 extending transversely of the drift and provided with the usual air-tight doors 11, 11, so that the drift and the working may be completely isolated from the shaft and all air excluded from the working, entrance and exit to the working being effected through the air-lock, in the usual manner, as will be understood. The miners, or other operators, equipped with respiratory apparatus, enter the working by way of the drift and they operate any of the well known types of ma-

chinery necessary for breaking down the oil bearing stratum, provided, however, that, if any pneumatic machinery is employed, the same be operated by compressed gas instead of air, the gas preferably being that recovered from the mine.

In most instances, the pressure of gas developed in the working will be heavier than that of the atmosphere and will serve to exclude any air which might tend to seep into the working. In case the gas pressure developed in the working is not equal to that of the atmosphere, it is proposed to supply the necessary deficit by an extra supply of gas forced into the working, which deficit supply may be taken from gas collected or stored from prior operations, or artificially produced. In order to withdraw the surplus gas in the working, there is provided a suction pipe 20, which extends along the drift and is connected to a pump or blower 21, which withdraws the surplus gas and delivers the same by pipe 22 to a suitable reservoir or gasometer 23 or, if desired, to an appropriate plant where the gas may be treated for the extraction of gasoline or other constituents. If the gaseous pressure in the working should fall below that of the atmosphere, the supply pipe 25 is provided for delivering the proper amount of gas from an extraneous source to the working, the pipe or main 25 being provided with a suitable blower 26 to force the external supply of gas into the working.

If desired, means may be provided for supplying the chamber or air-lock between the partitions 10, 10 either with gas similar to that found in the working, or with air, in order to facilitate the operation of the lock in the transfer of men and material to and from the working. As indicated, a manifold 30 is located in the upper part of the air-lock and is connected to a combination pump and blower 31, which is connected by main 32 to gasometer 35, said main having a lateral branch 34 communicating with the atmosphere and controlled by a threeway valve 33, which latter may connect up the air-lock directly with the gasometer or with the atmosphere as the case may be, so that the lock may be filled either with gas or with air, depending upon whether the traffic is entering or leaving the working, as will be understood.

The working will preferably be equipped with the usual accessories, such as a tram-

way for conveying materials between the working and the shaft. Likewise the working will be provided with a suitable sump 15 to collect the oil freed from the sands, which sump is connected with the pipe-line 16 provided with a pump 18 for delivering the oil to a suitable reservoir 19.

Under the conditions described, the mining operations may be carried out with facility and by means of the usual tools and accessories, including electrically or pneumatically operated machines, and with the concomitants of ordinary gas free mining operations, including electric tramways, electric lights and power circuits, without danger of explosions, as the gaseous atmosphere maintained in the working is not explosive unless admixed with air or an oxygen supplying gas.

It will be understood that the method can be practiced in mining operations of various characters and extents and is not limited to mining oil bearing deposits, but is applicable to all mining operations which are accompanied by the production or liberation of gases dangerous to human life, either because of the combustibility thereof, when mixed with air, or due to their lethal characteristics, the only precautions necessary being the exclusion of air from the workings and the equipment of the operators with proper respiratory apparatus.

What I claim is:

1. The method of mining oil deposits and other lethal or combustible gas producing deposits, which comprises isolating the gas producing workings by suitable barriers, constantly maintaining an atmosphere of such gas in said workings at a pressure substantially greater than atmospheric, and to prevent the entrance of air therein, and effecting the excavating and removal operations in said atmosphere.

2. The method of mining oil deposits and other lethal or combustible gas producing deposits, which comprises isolating the gas producing workings by suitable barriers, constantly maintaining an atmosphere of such gas in said workings at a pressure substantially greater than atmospheric, and to prevent the entrance of air therein, withdrawing surplus gas for utilization, and effecting the excavating and removal operations in said atmosphere.

In testimony whereof I affix my signature.
EWART G. SINCLAIR.
